WINDOW SCREEN

Herbert I. Fogelberg, St. Paul, Minn.

Application August 5, 1937, Serial No. 157,549

6 Claims. (Cl. 156—14)

The present invention relates to a window screen, and more particularly to a window screen adapted for use with a pivoted closure member of the flush mounting type, such as is illustrated and described in my pending application, Serial No. 157,548, filed simultaneously herewith.

In a frameless type of window structure, such as that illustrated and described in the above application, it is desirable that the screen frame be adapted for mounting without the use of bolts or screws or other fastening means which necessitates a penetration of the structure upon which the screen is mounted.

An object of the present invention is to make an improved and simplified window screen frame.

Another object is to make a screen frame for a closure member with a portion of the screen frame being positioned to be engaged by a closure element to provide a substantially weather tight seal between the closure member and the adjoining structure.

Another object is to make a screen for a window opening, said screen having a frame with a reversely curved portion thereof, adapted to have clip engagement with the structure surrounding said opening.

In order to attain these objects, there is provided, in accordance with one feature of the invention, a frame having a reversely bent flexible flange projecting inwardly therefrom and adapted to have clip engagement with a bead provided on the structure surrounding an opening adapted to receive said frame; said frame having a second portion spaced inwardly from said flange portion which is adapted to have resilient sealing engagement with a closure member mounted in said opening. The frame may be in the form of an ornamental channel member and may be filled with a resilient substance such as rubber.

These and other features of the invention will be more fully set forth in the following description and accompanying drawing, wherein,

Figure 1 is a view in side elevation of a fragment of a glass block wall structure having a window opening therein, and having a screen embodying the present invention mounted thereon.

Figure 2 is an edge view of the screen shown in Figure 1.

Figure 3 is a sectional view on the line 3—3 of Figure 1, and,

Figure 4 is a fragmentary sectional view on the line 4—4 of Figure 1.

Referring to the drawing in detail a wall 1 is of

glass block structure, similar to that of my co-pending application, Serial No. 157,548 for a closure member which is pivotally mounted in an opening 2. The edges of the blocks 2 on each side of the opening have a flange 3 extending inwardly and having the inner faces 4 thereof arcuately curved on an arc concentric with edges 5 and 6 of the closure member 1. Beads 7 and 8 are provided on the outer edge of the closure member. A frame 9 of a screen comprises a rectangle having the four sides thereof formed of a metallic channel member 10 with an edge portion 11 bent inwardly to have the inner surface thereof parallel to the plane of the screen frame. A screen cloth member 12 is secured to the inner face portion 11 as by soldering. From the outer end of the portion 11, the metal strip 10 is bent downwardly in a curve as at 13. From the lower edge of the curved portion 13, the metal is again bent outwardly in the form of curve 14, adapted to have fitting engagement with the beads 7 and 8 of the closure member 1. From the lower outer end of the curved portion of strip 10, the metal strip is bent inwardly as at 15 in a plane parallel to the screen cloth 12 and from the inner end of this portion, the metal is curved downwardly as at 16 to have fitting engagement with the edge portion of the flange 3. The frame strip thus formed may be filled with a resilient substance 17, such as rubber, although this filling is not essential to the invention. The flanges 18 and 19 (see Figures 2 and 4) are not curved as are the side flanges 16, but extend straight inwardly, perpendicular to the plane of the screen cloth 12, and are inserted between a glass wall block 22 and a cork sill strip 21.

To mount the screen in a window opening, it is necessary to place the screen in position over the window opening and forcibly press the screen frame against the curved edges of the flanges 3 thereby forcing the clip portions 16 inwardly toward the center of the opening until the lower edges of the clip portions 16 pass the center of curvature of the edge portion of the flange 3 at which point the resilient outward pressure of the clip portions 16 will exert a cam-like action to draw the screen inwardly to the position shown in Figure 3.

The device comprises a simple, attractive and inexpensive screen construction for windows of the type illustrated, which is readily and firmly mounted in position without the use of extraneous fastening means. The structure has the advantage of providing a weather tight seal across the joint between the window opening and the

window which provides an effective seal against draft and the loss of heat through the joint. The side clip portions 16 should be free from the flanges 18 and 19 at the top and bottom of the screen frame, respectively, to permit free inward displacement of the clip portions 16 when mounting the screen in a window opening.

I claim:

1. A window screen for mounting in a window opening having a bead on the inner side thereof; and having a window mounted therein comprising a frame, a spring clip member mounted to have clip engagement with a bead on a window opening and having a sealing portion spaced from said clip portion and resiliently mounted with respect to said clip portion, said sealing portion being positioned to be engaged by a window mounted in said window opening on closing said window, the space between said clip member and said sealing member being joined by a non-permeable element to provide a weather-tight seal between said head and said window with said window in a closed position.
2. A window screen for mounting in a window opening having a bead on the inner side thereof and having a window mounted therein; comprising a frame having a spring clip member mounted to have clip engagement with a bead on a window opening.
3. A window screen for mounting in a window opening having a window pivotally mounted therein; comprising a frame, securing means mounted to hold said frame in close engagement with an area surrounding a window opening, a resiliently mounted strip carried by said frame and positioned to be engaged by a window on closing said window, the space between said frame and said strip being closed to provide a weather

tight seal between said window and said window opening.

4. A window screen for mounting in a window opening having a window mounted therein; comprising a frame securing means mounted to hold said frame in close engagement with an area surrounding a window opening, a resiliently mounted strip carried by said frame and positioned to be engaged by a window on closing said window, the space between said frame and said strip being closed to provide a weather tight seal between said window and said window opening.

5. A window screen for mounting in a window opening having a window pivotally mounted therein; comprising a frame, securing means mounted to hold said frame in close engagement with an area surrounding a window opening, a resiliently mounted strip carried by said frame and positioned to be engaged by a window on closing said window, the space between said frame and said strip being filled with a compressible non-permeable substance to provide a weather tight seal between said window and said window opening.

6. A window screen for mounting in a frameless window opening having a bead on the inner side thereof and having a window pivotally mounted therein; comprising a frame, a spring clip member mounted on said frame to have clip engagement with a bead on said window opening, said frame being formed of a channel of sheet metal continuous throughout its width and having a sealing portion spaced from said clip portion to be engaged by a window pivotally mounted in said window opening to provide a weather tight seal between said bead and said window with said window in a closed position.

HERBERT I. FOGELBERG.
